Michael Nuhn

UNITED STATES PATENT OFFICE.

MICHAEL NUHN, OF NEW YORK, N. Y., ASSIGNOR TO JAMES L. JACKSON & BROTHER, OF SAME PLACE.

DESIGN FOR RACK FOR ROBES.

Specification forming part of Design No. 5,423, dated December 12, 1871.

To all whom it may concern:

Be it known that I, MICHAEL NUHN, of the city and State of New York, have invented or made a Design for Racks for Robes, &c.; and the following is declared to be a correct description thereof.

This design relates to the metal casting carrying the swinging arms upon which robes, horse-blankets, or similar articles can be hung in a stable.

This design is shown in the annexed drawing by a perspective view.

The plate *a* has projecting from it the tapering arms *b b*, at the ends of which are short cylindrical hubs *c*. The circular heads *d d* are between

these arms *b*, and turn in the hubs *c*. The brackets *f f* are of the shape and configuration represented, and they receive the wooden arms *g g*. The shape of each bracket is that of a right angle, with a strengthening arch on one side; and pins or bolts connect these brackets and circular heads together.

I claim—

The design of the castings for the robe-bracket, as described and represented.

Signed by me this 14th day of July, A. D. 1871.
MICHAEL NUHN.

Witnesses:

CHAS. H. SMITH,
GEO. T. PINCKNEY.
